(57) **CLAIM**

The ornamental design for a submersible cage as shown and described.

DESCRIPTION

FIG. 1 is a front perspective view of a submersible cage showing our new design;

FIG. 2 is a right side view thereof;

FIG. 3 is a left side view thereof;

FIG. 4 is a front view thereof;

FIG. 5 is a back view thereof;

FIG. 6 is a top view thereof;

FIG. 7 is a bottom view thereof;

FIG. 8 is a right cross section view thereof;

FIG. 9 is a front perspective view of a submersible cage showing our new design;

FIG. 10 is a right side view thereof;

FIG. 11 is a left side view thereof;

FIG. 12 is a front view thereof;

FIG. 13 is a back view thereof;

FIG. 14 is a top view thereof;

FIG. 15 is a bottom view thereof; and,

FIG. 16 is a right cross section view thereof.

The broken lines in the drawings depict portions of the submersible cage that form no part of the claimed design.
